SHEET METAL ROOFING

Gabriel J. Key, Ararat, N. C.

Application August 19, 1940, Serial No. 353,285

1 Claim. (Cl. 108—22)

This invention relates to sheet metal roofing, and its general object is to provide an interlocking lap joint for metallic roofing sheets and the like, in which the joint portions are shaped and interlocked in a manner to not only bring about concealment or covering of the edges of the sheet and the fastening nails therefor, but to prevent any possibility of seepage of water between the joint portions or casual separation or displacement thereof, due to expansion and contraction or wind, with the result my joint is retained weathertight under all conditions.

A further object is to provide a lap joint for metallic roofing sheets, which makes it possible to lay the sheets and to fasten the same in an easy and expeditious manner, and notwithstanding the many advantageous features of the joint, it is very simple in construction, thus sheets or shingles including my joint portions can be inexpensively manufactured.

This invention also consists in certain other features of construction and in the combination and arrangement of the several parts, to be hereinafter fully described, illustrated in the accompanying drawing and specifically pointed out in the appended claim.

In describing the invention in detail, reference will be had to the accompanying drawing wherein like characters denote like or corresponding parts throughout the several views, and in which:

Figure 1 is a fragmentary perspective view illustrating roofing sheets constructed in accordance with the present invention and laid and fastened to provide a roof.

Figure 2 is a fragmentary perspective view of one of the sheets.

Referring to the drawing in detail, the letter A indicates the usual sheathing upon which the sheets are laid and fastened by nails or the like B to provide the roof, and while I have illustrated three sheets for that purpose, as shown in Figure 1, and having my joint portions formed thereon, with the companion portions of adjacent sheets overlapped and interlocked, each sheet is identical, and is best shown in Figure 2.

Each sheet which is preferably of elongated rectangular formation, is broadly indicated by the reference numeral 1 and is shaped by any method to form three longitudinally extending inverted cross sectional assembly V-shaped parallel arranged ridges 2, 3 and 4, merging one into the other and disposed adjacent one longitudinal edge of the sheet to provide a relatively narrow flat outer portion 5. While the inner

and outer ridges 2 and 4 may be of the same height the intermediate or middle ridge 3 is of less height than the other two, and the metal from the apex of the inner ridge 4 is crimped together to provide a double thickness and folded downwardly toward the inner sloping wall of the ridge 4, but is spaced therefrom to form a longitudinally extending channel hook 6 throughout the length of the sheet, as will be apparent.

Both of the outer walls of each of the ridges or corrugations 2 and 4 are of the same height, so that the flat outer portion 5 and the flat intermediate or body portion 7 of the sheet are normally on the same level, as clearly shown in Figure 2, and the sheet is shaped adjacent to its opposite longitudinal edge to form an inverted cross sectional substantially V-shaped ridge 8 having an inner sloping wall of substantially the same height as that of the sloping walls of the ridges 2 and 4, but the outer sloping wall of the ridge 8 terminates at its lower longitudinal edge, a considerable distance above the inner sloping wall thereof, and has formed on its lower edge an elevated flat portion 9 from which extends an upwardly directed outwardly sloping flange 10.

From the above description and the disclosure in the drawing, particularly Figure 1, it is believed that the manner of laying the sheets and interlocking the joint portions together, will be obvious, but it might be mentioned that the sheets are laid on the sheathing A and fastened by nails B or the like, which extend through the flat outer portions 5 only, and after one sheet is laid and fastened, the adjacent sheet is interlocked therewith, by placing the flange 10 within the hook 6 of the first sheet, for disposal of the flange between the inner sloping wall of the inner ridge 4 and the hook, for the latter to set up a clamping engagement with the flange. When so disposed, the flat portion 9 of the second sheet rests upon the middle ridge 3 of the first sheet and the sloping walls of the ridge 8 rest upon the sloping walls of the outer ridge 2, for the disposal of the body portion 7 of the second sheet upon the flat outer portion 5 of the first sheet for covering the same and consequently the nails B. Thence the second sheet is fastened to the sheathing and the succeeding sheets are laid and fastened in the same manner, until the roof is completed, thus it will be seen that the sheets are not only interlocked with each other and the joint prevents any possibility of separation or casual displacement of the sheets, but the outer longitudinal edges of

the sheets, as well as the nails are completely covered, as clearly shown in Figure 1.

It is thought from the foregoing description that the advantages and novel features of the invention will be readily apparent.

It is to be understood that changes may be made in the construction and in the combination and arrangement of the several parts, provided that such changes fall within the scope of the appended claim.

What I claim is:

In a joint for metallic roofing sheets, each sheet being formed with inner, intermediate and outer parallel ridges adjacent one edge thereof, the intermediate ridge being of less height than the inner and outer ridges and each of the ridges being of inverted cross sectional substantially V-shape, an outer flat portion extending from the outer ridge to said edge and adapted to receive fastening means, channel hook means formed along the inner ridge and extending downwardly from the apex thereof toward the intermediate

ridge for disposal in spaced relation with respect to the inner wall of the inner ridge, a single ridge adjacent the opposite edge of the sheet and being of inverted cross sectional substantially V-shape, said single ridge having a short outer wall, an inner flat portion between the single ridge and said inner ridge, a flat portion formed on the short wall of the single ridge to be elevated above the other flat portions and extending outwardly

from the short wall, a flange formed on the elevated flat portion and extending at an inclination outwardly and upwardly therefrom, and the flange of one sheet adapted to be clamped between the hook means and the inner wall of the inner ridge of an adjacent sheet for disposal of the elevated flat portion of the first sheet upon the intermediate ridge and between the inner and outer ridges of the second sheet, as well as the single ridge upon the outer ridge and the inner flat portion of the second sheet upon the outer flat portion of the first sheet.
